TURBINE CONSTRUCTION

Axel W. Carlson, Worcester, Mass., assignor to
 Carling Turbine Blower Co., Worcester, Mass.,
 a corporation of Massachusetts

Application June 6, 1938, Serial No. 212,091

2 Claims. (Cl. 253—77)

This invention relates to turbines operable by steam, air, or other gaseous media and in which closely associated buckets are provided on the periphery of the rotor and commonly also on the associated fixed turbine casing.

The blades which separate the bucket spaces are necessarily of limited cross section and are subject to the erosive action of steam or gas and are also subject to centrifugal stresses developed by the high speed of the rotor.

It is the general object of my invention to improve the bucket construction in such turbines in such manner that more resistant material may be used in the turbine blades and that the blades may be more securely mounted in the rotor and may be firmly held from angular displacement.

My invention further relates to arrangements and combinations of parts which will be hereininafter described and more particularly pointed out in the appended claims.

A preferred form of the invention is shown in the drawing, in which

Fig. 1 is a sectional elevation of parts of a turbine embodying my improvements;

Fig. 2 is a sectional side elevation of the rotor, taken substantially along the line 2—2 in Fig. 1;

Fig. 3 is a detail plan view of the rotor, looking in the direction of the arrow 3 in Fig. 2;

Fig. 4 is a sectional side elevation of a portion of a fixed member and blades, taken along the line 4—4 in Fig. 1;

Fig. 5 is a front elevation of one of the blades;

Fig. 6 is a side elevation thereof, looking in the direction of the arrow 6 in Fig. 5; and

Figs. 7 and 8 are end views of the blade, looking in the directions of the arrows 7 and 8 respectively in Fig. 6.

Referring to the drawing, I have shown portions of a turbine comprising a casing 10 and a rotor 11 mounted on a shaft 12^a. First and second series of movable buckets are formed on the rotor 11 by blades 12 and 14 respectively, and a third series of buckets is formed on a fixed segmental member 15 by blades 16. The member 15 is rigidly secured in the casing 10 in any convenient manner, as by a dove-tail flange 17, and the stationary blades 16 project between the movable blades 12 and 14, as clearly shown in Fig. 1.

The blades 12, 14 and 16 are substantially alike, except for differences in longitudinal proportions, and are preferably formed from wire rod of special composition and drawn to the special concavo-convex section indicated in Figs. 7 and 8.

The blades 12, as shown in Figs. 5 to 8, are each provided with a body portion 20, a short outer projection 22 and a longer inner projection or shank 24. These projections are preferably of circular cross section and may be produced by removing portions of the wire rod by turning, milling or grinding operations.

The blades 12 are further subjected to a milling operation or to some similar procedure by which the lower outer corners of the blades are cut away or notched, as indicated at 25, to provide shoulders 26 in the opposite edge portions of the blades.

The blades 14 are similar in construction to the blades 12, except for differences in length, and the blades 16 are also similar in construction but are inverted when in operative position.

The rotor 11 is provided with flanges 30 and 31 to receive the blades 12 and 14 respectively, and these flanges are provided with transverse grooves 32 separated by ribs 33. A radially extending hole 34 is associated with each groove 32.

When the rotor is assembled, the shank portions 24 of the blades 12 and 14 are inserted in the holes 34, with the ribs 33 positioned in the notches 25 and closely engaged by the shoulders 26 on the body portion 20 of each blade. After being thus assembled, the inner ends of the shank portions are riveted or spun over, as indicated at 35 (Fig. 1), to securely hold the blades in position.

A band or shroud 39 is then mounted outside of the blades 12 or 14, said band having openings to receive the outer projections 22. One of the blades in each set, as 14^a in Fig. 2, is shortened so that both ends of the band 39 may be secured while leaving the outer surface of the band concentric. The projections 22 are riveted or spun over on the band 39 as previously described.

The fixed segmental members 15 are similarly provided with transverse grooves 40, ribs 41 and radial openings 42, and the blades 16 are mounted therein, all as previously described. An inner band or shroud 44 is preferably provided, in which the inner ends of the blades 16 are riveted or otherwise secured.

The several sets or series of blades are mounted with such running clearance as is desirable, and any usual nozzles or other devices may be provided for supplying steam or other gas to the rotor. These features, however, form no part of my present invention, which relates particularly to the construction of the bucket blades and to the

manner of securing the same in the rotor 11 or in the segmental members 15.

By making the blades from separate rolled stock instead of forming the blades integral with the rotor, I am able to use material specially adapted for blade purposes. The rolling operation also provides a surface layer which is tougher and more resistant to erosion than can be readily obtained in blades produced by machine operation.

10. The provision of the notches 25 and shoulders 26 is particularly important, as the engagement of the shoulders 26 with the ribs 33 or 41 effectively prevents any angular displacement of the blades, either in the rotor 11 or in the stationary member 15. The mechanical operations on both the blades and the rotor are easily performed, as is also the assembling of the blades in the rotor or stationary member.
15. Having thus described my invention and the advantages thereof, I do not wish to be limited to the details herein disclosed, otherwise than as set forth in the claims, but what I claim is:

1. In a turbine, a rotor having a rim provided with axially extending transverse grooves and intervening transverse ribs and also provided with radial openings extending into said grooves, and rotor blades provided with shanks fitting said openings and secured therein and each provided with two substantially spaced shoulders engaging the same side of an adjacent transverse rib perpendicular of said rib and at each side of the associated radial opening, thereby preventing angular displacement of said blade in said rotor.

2. In a turbine rotor, a bucket blade having a body portion of concavo-convex section and having integral end projections of circular cross section, and said blade having notches at one end of said body portion providing substantially spaced shoulders with engaging surfaces aligned in a single plane and disposed at opposite sides of one of said projections and by which engaged shoulders said blade will be positively held from angular displacement in said rotor.

AXEL W. CARLSON.
